UNITED STATES PATENT OFFICE.

HENRY C. SPINNEY, OF LYNN, MASSACHUSETTS, ASSIGNOR TO THE GENERAL ELECTRIC COMPANY, A CORPORATION OF NEW YORK.

ELECTRIC-ARC LAMP.

SPECIFICATION forming part of Letters Patent No. 691,821, dated January 28, 1902.

Application filed July 20, 1898. Serial No. 686,411. (No model.)

To all whom it may concern:

Be it known that I, HENRY C. SPINNEY, a citizen of the United States, residing at Lynn, in the county of Essex, State of Massachusetts, have invented certain new and useful Improvements in Electric-Arc Lamps, (Case No. 797,) of which the following is a specification.

In electric-arc lamps having a small cylinder or globe surrounding the arc, with clutches working directly on the carbon, it has been customary to utilize the cap of the cylinder as a floor for tripping the clutch. This arrangement presents several advantages, among others that it permits the lamp to be shortened, is more economical in the use of carbon, and renders the parts more accessible to the trimmer. Within certain limits this arrangement is satisfactory; but where cylinders of different makes or varying heights are employed the tripping-point of the clutch is varied, and therefore it is necessary to adjust the lamp to a greater or less degree. To overcome the objections and at the same time retain the advantages above pointed out, I mount the floor of the clutch in such a manner that it is situated at or about the height of the cylinder-cap, but separate therefrom.

With arc-lamps having detachable caps for the arc-inclosing cylinders it often happens that the trimmer will drop the cap as he is trimming the lamp. This is a particularly objectionable feature, for practically each time a cap is dropped it means that a new outer globe must be supplied to the lamp. It is also objectionable even in lamps without outer globes, as it necessitates the trimmer descending from his ladder to pick up the cap. These caps due to their proximity to the arc get very hot, so that they cannot be handled without the use of pliers or some similar device, and it is while handling them in this manner that they most frequently drop and break the outer globe. On account of the variations in the cylinders it is desirable that these caps shall be so supported that they are free to adjust themselves in a vertical and horizontal direction. This is accomplished by permitting the caps to rest on the top of the cylinder. To prevent the cap from dropping and at the same time permit it to ad-

just itself, I provide a support which is so arranged that the cap is permitted to move freely up and down within certain limits and also laterally for the purpose of adjustment, 55 but is prevented from dropping to a point where it will endanger the globe.

My invention has for its object to improve the construction of inclosed-arc lamps; and to that end it consists in the parts and combination of parts as herein described and claimed.

In the accompanying drawings, which show an embodiment of my invention, Figure 1 is a partial front elevation of a lamp with the outer globe in section. Figs. 2 and 3 are respectively a side elevation and plan of the cap-support and floor for the clutch, and Fig. 4 is a perspective view of a slight modification.

Secured in any desirable manner to a fixed portion of the lamp is a flat substantially circular support or cage A. In the present instance the support is carried by two vertically-extending posts B and B', which are secured to the under side of the lamp-base C. The center of the support is provided with an opening K, through which the upper carbon moves in a free and unobstructed manner. At the lower end of each post is a long screw B², and by substituting screws of different length the position of the support or cage A 70 may be adjusted as desired, either for the purpose of regulating the tripping of the clutch or for changing the position of the cap. This is a desirable feature where adjustments of a radical nature are desired; but for simple adjustments the freedom of movement permitted to the cap D, to be hereinafter described, is sufficient to compensate for changes in the heights and other irregularities of the different cylinders. The support is shown rigidly 75 secured in place by two upwardly-extending lugs A', through which extend the screws B²; but this construction may be varied as desired. The cylinder-cap D is loosely suspended from the under side of the support or cage A by means of the hooked lugs A² and the screw A³, the latter being mounted in an extension A⁴ of the support. The lugs and screw are so arranged that they support the cap at three points, which points are angularly displaced by one hundred and twenty degrees. 80 I have found this to be a convenient arrange- 85

ment, for by taking out the screw A³ the cap may be removed; but any other means for suspending the cap may be employed. The distance between the under side of the support 5 and the hooked end of the lugs is considerably greater than the thickness of the cap. This is to permit the cap to have a certain freedom of movement in a vertical direction to compensate for the varying heights of the cylinder E. By this arrangement cylinders may be employed which differ materially in their height. A space is left between the cap and its supports to permit the former to have more or less lateral adjustment to compensate for 10 irregular cylinders. The cap when supported in the manner shown has great freedom of movement and will readily adjust itself with respect to the cylinder and so long as the cylinder is anywhere near the proper size and 15 shape will work in a satisfactory manner.

One decided advantage of the construction shown lies in the fact that the cap does not have to be made special in any particular and also that the cage A may be applied to lamps 20 already in use.

The cylinder E surrounds the carbons G and G' and is secured at its lower end to the lamp-frame H by a suitable clamp or holder F. Normally the cap D rests on the top of 25 the cylinder and is supported thereby, the support or cage A only coming into play when the cylinder is removed.

Surrounding the upper carbon G is a tube I, and carried by the end of the tube is a clutch J of any suitable construction. The one shown is arranged to work directly on the carbon and consists of a pair of pivoted jaws J' and J², which are united by links J³ with a collar I', carried by the tube I. The extensions on the jaws J' and J² are arranged to strike the top of the support A, which constitutes the floor of the clutch. As shown the clutch is in its extreme lower position and the carbon is released. By situating the floor of 40 the clutch at a fixed distance from the base of the lamp the clutch J will trip at a certain point each time the tube I, which is connected to the lamp-actuating mechanism, drops a certain amount, whereas with the cap itself 45 arranged to act as the floor of the clutch the action is not so definite.

In Fig. 4 I have illustrated a slight modification of my invention, in which a special cylinder-cap is employed having lugs a formed integral therewith. These lugs are 50 provided with holes for the reception of the supporting-screws B², the relation between the parts being such that the cap is free to adjust itself in a vertical direction and also 55 to tilt slightly to compensate for irregular cylinders. Supported by shoulders formed on the screws B² is a flat plate A, having a central opening K for the carbon, which acts as the floor of the clutch. This plate is preferably fixed with respect to the bottom of the lamp; but, if desired, it may be capable of 60 movement toward the lamp-base, the chief

requisite being that it shall have a definite seat, so that adjusting of the carbon-clutch is unnecessary.

The cap for the cylinder comprises two parallel plates or flanges which are connected by a central hub, the upper flange being provided with lugs for the reception of the screws B², while the lower flange is arranged to fit 70 inside of the cylinder and assist in forming an air-chamber. It will be seen that the holes in the plate A are larger than the screws B². This permits the plate to rock slightly on a horizontal axis for the purpose of adjustment 75 and also permits one side of the plate to move slightly in a vertical direction. This arrangement constitutes, in effect, a support having a universal movement.

I understand that I am not the first to make 80 a floor for a carbon-clutch which is located at a fixed point with respect to the lamp; but in all of the lamps with which I am familiar the clutch-floors are located at or near the base of the lamp or else the cylinder-cap is 85 utilized to act as the floor of the clutch. For certain purposes the former arrangement may be employed; but it is not so economical in the use of carbon, as the piece remaining in the lamp is not long enough to use as an upper carbon, and it is too long to use as a lower carbon. With the clutch having a fixed floor 90 and working at a point below the base and near the cylinder-cap I am enabled to materially shorten the lamp, to economize in the 95 use of carbon, and to utilize the remaining piece of the upper carbon, when retrimming, as the lower carbon, and this without changing its length.

I believe that it is broadly new with me in 100 connection with an inclosed-arc lamp to suspend the cylinder-cap in such a manner that while it is free to adjust itself with respect to the cylinder to compensate for irregularities therein it is prevented from dropping 105 from the lamp when for any reason the cylinder is removed.

What I claim as new, and desire to secure by Letters Patent of the United States, is—

1. In an electric-arc lamp, the combination 115 of a globe or cylinder which incloses the carbons, a cap which rests on the top of the cylinder and prevents the free entrance of air into the cylinder, and a cage or support for the cap which is normally out of use, but 120 which retains the cap at or near its normal position when the cylinder is removed.

2. In an electric-arc lamp, the combination 125 of a globe or cylinder which incloses the carbons, a cylinder which surrounds the carbons, a cap supported by the cylinder during the normal operation of the lamp, a cage or support normally idle, in which the cap is loosely mounted, but so arranged that it will prevent the cap from falling when the cylinder is removed, and means for suspending the cage or support from a fixed part of the lamp.

3. In an electric-arc lamp, the combination 130 of a cylinder which surrounds the carbons, a

cap which rests on the top of the cylinder, a cage surrounding the cap and preventing it from falling, the said cage being provided with downwardly-extending lugs which support the cap at more than one point.

4. In an electric-arc lamp, the combination of a cylinder which incloses the arc, a cap arranged to rest on the cylinder and be supported thereby under normal conditions, a cage for retaining the cap within the lamp when the cylinder has been removed, the said cage being provided on its under side with means for supporting the cap at three points.

5. As an article of manufacture, a support or cage for a cylinder-cap, comprising a metal body having lugs for securing it to the lamp-frame, hooked lugs for gripping the cap, and a detachable support permitting the removal of the cap.

20 6. In an arc-lamp, the combination of a cylinder, a cap therefor, a support for the cap, and downwardly-extending lugs on the support, which retain the cap in place when the cylinder is removed.

25 7. In an inclosed arc-lamp, the combination of a combined support for the cap of the inclosing globe and floor for a clutch, with means for limiting the downward movement of the support, so arranged that freedom of adjustment for the cap is permitted.

30 8. In an arc-lamp, the combination of a

combined cap-support and floor for a clutch, means for maintaining it at a fixed distance from the lamp mechanism, and means for permitting the support to have practically a 35 universal motion for the purpose of adjustment.

9. In an arc-lamp, the combination of a combined cap-support and floor for a clutch, a screw - threaded support for holding the 40 cap-support in place, an upwardly-extending lug forming the support through which the screw-threaded support extends, and means permitting the cap to adjust itself, but preventing it from falling out of the lamp. 45

10. As an article of manufacture, a support for a cylinder-cap, comprising a flat metal plate having a pair of upwardly-extending supporting-lugs, and a pair of downwardly-extending lugs for retaining the cap. 50

11. As an article of manufacture, a cylinder-cap, comprising two parallel flat cylindrical flanges one of less diameter than the other connected by a hub, one of the flanges being provided with an extension for supporting the cap. 55

In witness whereof I have hereunto set my hand this 16th day of July, 1898.

HENRY C. SPINNEY.
